UNITED STATES PATENT OFFICE.

OWEN J. McGANN, OF PITTSBURG, PENNSYLVANIA.

FLUSHING APPARATUS FOR WATER-CLOSETS AND OTHER SANITARY APPLIANCES.

SPECIFICATION forming part of Letters Patent No. 357,218, dated February 8, 1887.

Application filed April 29, 1886. Serial No. 200,524. (No model.)

To all whom it may concern:

Be it known that I, OWEN J. McGANN, a citizen of the United States, residing at Pittsburgh, in the county of Allegheny and State of Pennsylvania, have invented certain new and useful Improvements in Apparatus for Flushing Water-Closets and the Like, of which the following is a specification.

This invention relates to an improvement in flushing apparatus particularly adapted for washing out sanitary appliances—such as water-closets—and provided with a service or flushing tank which is supplied from a valved service-pipe and emptied by a siphon discharge-pipe.

The objects of my improvement are to provide for flushing the water-closet or other article to be washed out at regular intervals for a desired period of time, and, after the supply has been cut off and the discharge through the siphon discharge-pipe has ceased, to effect a supplemental discharge by discharging the water remaining in the tank and standing in the supply-pipe between the tank and the supply-valve, thereby providing for a quick ultimate discharge into the article to be cleansed of a body of water that shall effect a final wash-out; second, to provide certain improved details of construction tending to the general efficiency of the apparatus.

In an apparatus embodying the principles of my invention the flow of water from the service or supply pipe to a service or flushing tank is established or cut off by a supply-valve; that may be operated in any suitable way—for example, by any of the methods common in water-closets. Thus, for instance, it can be controlled by hand or by the position of a hinged seat held down by the weight 40 of the occupant and automatically raised as soon as it is vacated.

Provision is made whereby, when the supply-valve for controlling the flow of water to the flushing-tank is open, the water from the latter shall be intermittently siphoned off and conducted to the water-closet or other sanitary appliance to be flushed, each discharge or flow being established as soon as the water has risen to some determinate height in the tank. 50 As soon, however, as the flow of water from the service-pipe is cut off, the valve of a valved supplemental discharge-pipe connected with

the said service or supply pipe is opened, which permits all of the water not previously siphoned off from the tank and also the water 55 remaining in the supply-pipe between the supply-valve and the tank to flow back through the supply-pipe and to the water-closet or other article, thus providing a supplemental discharge for effecting a final wash-out. The 60 two valves for such purpose are desirably connected, so that the impulse that closes one valve shall open the other.

In the drawings illustrating an apparatus embodying the principles of my invention, 65 Figure 1 represents, in perspective, my improved apparatus applied to a water-closet; Fig. 2, a sectional detail showing more particularly the valve mechanism.

In said drawings, A indicates the flushing-tank, that can be open at the top, as herein shown; or, if desired, it can be closed and provided with any suitable construction of air-inlet valve. Water is supplied to this tank through the pipe B, that enters the tank and 75 terminates therein at or about the bottom, so that when said pipe is used as a discharge instead of a supply pipe all water within the tank may be drawn off.

C denotes the pipe by which water is intermittently siphoned off from the tank. For this purpose the pipe extends up into the tank and has its end portion within the latter bent down, so as to form an inverted-U bend, that serves to provide the two legs of a siphon. 85

The pipe B is connected both with the service-pipe D and with the water-closet, with which latter the pipe C is likewise connected, a simple and convenient way being to connect both of the pipes B and C with a pipe or joint, 90 B', that can have a lateral branch, b, so as to afford a passage leading from both the pipes B and C to the bowl. A valve, E, is arranged to open and close communication between the pipe B and the service-pipe, and a valve, E', 95 is arranged to open and close communication between said pipe B and the water-closet or the pipe B', constituting a passage leading to the water-closet or other like appliance. The pipe B has at a point below the tank two ports—100 the one for connecting it with the service-pipe and the other for connecting it with the pipe or passage leading to the bowl or like article that is to be flushed. Said pipe C is shown

connected with the bowl of the water-closet or with the article to be flushed by the pipe B' and the lateral branch pipe b, that leads from said pipe at a point between the valve E and the tank.

5 The valves E and E' are connected by stems e and e', respectively, with the opposite ends of an oscillating lever, E², that is secured at about its ends upon an axis or pivot. The 10 lower portion of pipe B is expanded to form a casing, b', of appropriate internal area for the confinement and free operation of the said pivoted lever; or, of course, said expanded portion can be formed by a separate shell or casing. 15 This casing is provided with two lateral necks or couplings, by which it is connected with the service-pipe D and the passage through pipe B'. The neck or coupling b² for the service-pipe is constructed to provide a chamber 20 and seat for the valve E, and the neck or coupling b³ is constructed to provide a like chamber and seat for the valve E'.

The axis or spindle E² of the oscillating valve-lever is connected with a lever, pull-rod, 25 or with the seat of a closet in any convenient way. For example, it can be connected with a lever, F, by a rod, F', so that by operating the lever F the double valve can be controlled. No special limitation, however, is herein made 30 to the means for operating the lever E², to which the two valves E and E' are connected, since any of the ordinary methods may be used, such as a lever and weight, or lever and pull-rod, or a chain.

35 The valves are set upon their respective stems so that when the valve E is open to establish a flow of water from the service-pipe to the pipe B the valve E' will be closed, so as to cut off communication between the pipe B and the bowl or other article to be flushed, 40 and, conversely, when the valve E' is open, the valve E will be closed.

Communication being established between the service-pipe and the pipe B, water will 45 flow into the tank, and at each period that the water rises to a determinate height within the tank it will be siphoned off through the medium of pipe C and conducted to the bowl through pipes B' and C', thus intermittently 50 flushing the closet as long as the valve E is open. When, however, the valve E is closed, so as to cut off the supply from the service-pipe, and the valve E' opened, so as to establish communication between the tank and the 55 closet through the medium of pipe B, all water remaining in the tank will be immediately

discharged through pipe B and conducted to the closet, so as to effect a final wash-out.

As herein shown, the valve E closes with and opens against the pressure in the service-pipe, while the valve E' is held closed against said pressure when the valve E is open.

By adjusting the valves upon their respective spindles the converse of this arrangement can be attained, the valve E opening with the 65 pressure in the service-pipe and closing against the same, in which case, when the valve E is held open with the pressure, the valve E' will be closed with the pressure. This is due to placing each valve in a chamber, as shown, the valve in one case being adjusted to seat at the ends of the chambers nearest pipe B, and in the other case to seat at the ends of the chambers nearest the pipes D and B', respectively. 70

The service-pipe can be provided with a 75 cock, D', whereby it can be opened or closed or the flow of water regulated, and any suitable means can be devised for locking the valve-controlling device or mechanism, so as 80 to permit a long period of the intermittent flushing process.

What I claim as my invention is—

1. In a flushing apparatus, the combination, 85 with a tank, of a valved supply-pipe and a siphon discharge-pipe, both connected with the tank, and a valve supplemental discharge-pipe connected with the supply-pipe to provide for a final discharge from the tank and supply-pipe after the supply-valve of the latter has been closed and the valve of the supplemental discharge-pipe has been opened, 90 substantially as described.

2. In a flushing apparatus, the combination, 95 with a tank, of the valved supply-pipe and a siphon discharge-pipe, both connected with the tank, and a valved supplemental discharge-pipe connected with the supply-pipe to provide for a final discharge from both the tank and the supply-pipe after the supply-valve of the latter has been closed and the valve of the supplemental discharge-pipe has been opened, 100 the valves for the said supply and supplemental discharge pipes being connected with one another and operative simultaneously, but 105 adjusted whereby when one valve is opened the other valve shall be closed, substantially in the manner and for the purpose described.
